PROCESS FOR REMOVAL OF RADIOACTIVE CONTAMINANTS

Frank G. Morris, Spokane, Wash., assignor, by mesne assignments, to Purex Corporation, Ltd., a corporation of California

No Drawing. Filed July 23, 1956, Ser. No. 599,342
7 Claims. (Cl. 252—135)

This invention relates to the decontamination of surfaces on which are deposited radioactive materials, and is especially concerned with a novel composition and process for radioactive decontamination of the clothing of personnel handling radioactive materials.

In the manufacture and handling of radioactive materials, the equipment used in processing and the clothing of workers become contaminated with the radioactive materials to a degree where it becomes a health hazard to personnel. In the past, many such contaminated articles have been discarded because of uneconomical or impossible cleaning requirements. To alleviate this costly procedure, considerable research has been carried out on processes and compounds that will economically remove the radioactive contamination.

It has been known to employ a glassy phosphate in an effort to remove radioactive contamination from workers' clothing. It has also been known that sodium carbonate may be somewhat effective in the removal of radioactive contamination. These materials have been used either alone or in combinations with cleaning aids such as soaps and synthetic detergents. Also, other inorganic phosphates, inorganic silicates, citric acid and bentonite clays have been employed. None of these materials, however, used either alone or in combination have proven entirely effective. In many instances, even repeated cleaning with the same reagent will not reduce the level of radioactivity below the point of safety.

In copending application Serial No. 536,297, filed September 20, 1955, by Elmer L. Brevik, there is disclosed a composition effective for removal of radioactive contamination from surfaces, said composition essentially comprising an aqueous solution of a glassy phosphate and either ammonium carbonate or ammonium bicarbonate.

One object of my invention is to provide a composition and process for the efficient removal of radioactive contamination from surfaces.

Another object is the provision of a composition and procedure for the radioactive decontamination of clothing, such as coveralls used by personnel handling radioactive materials.

A still further object is to afford a relatively inexpensive composition and economical process for removal of radioactive contamination from surfaces, and to eliminate steps employed in conventional processes utilizing known compositions.

Other objects and advantages will be apparent from the following description of my invention.

I have found that a composition essentially comprising a polyphosphate, a nonionic or an anionic detergent, and a monohydroxy aliphatic monocarboxylic acid of from 2 to 3 carbon atoms, when used in a water solution, is highly effective in the removal of radioactive contaminants from surfaces, particularly clothing. My composition is especially valuable for removal of radioactive contaminants emitting alpha rays, but is also effective in re-

2

moval of radioactive contaminants emitting beta-gamma radiation.

The polyphosphates which I have found to be effective are the water-soluble crystalline polyphosphates and the water-soluble amorphous polyphosphates commonly called glassy phosphates, the glassy phosphates being preferred.

Representative water-soluble crystalline polyphosphates which I employ are the alkali metal or ammonium pyrophosphates of the empirical formula $M_4P_2O_7$ tripolyphosphates of the empirical formula $M_5P_3O_{10}$ and trimeta phosphates of the empirical formula $M_3(PO_3)_3$ and the acid salts of the above noted polyphosphates, such as $M_2H_2P_2O_7$ and $M_3HP_2O_7$, wherein M is an alkali metal such as sodium or potassium, or ammonium.

Glassy phosphates have been defined in the literature as condensed phosphates having a $Na_2O:P_2O_5$ ratio of from 0 to 1.7. The phosphate glass with a mol ratio of 1.0 has been called "Graham's salt," and sometimes referred to as hexametaphosphate of the formula $(MPO_3)_6$. The degree of polymerization of these glassy phosphates or polyphosphates is determined from their approximate analysis. See "Properties of the Chemistry of Phosphorus," John R. Van Wazer, Interscience Encyclopedia, Inc., 1953.

The glassy phosphates employed in my invention are polyphosphates which have a $M_2O:P_2O_5$ ratio of about 0.9 to about 1.3, M being an alkali metal such as sodium or potassium, or ammonium. The term "glassy phosphate" is employed herein to denote and include any or all of these materials. Preferably, the glassy phosphates which I employ are those which when dissolved in water in a concentration of about 31 grams per liter of solution give a pH of from about 6 to about 8.

When the polyphosphates preferably employed are sodium polyphosphates such as sodium tripolyphosphate and sodium hexametaphosphate, and the equivalent alkali metal, e.g., potassium, polyphosphates and the equivalent ammonium polyphosphates, mixed alkali metal polyphosphates can also be employed. Thus, for example, the polyphosphates of sodium in which the sodium cation is partially substituted with potassium or ammonium can be employed. The polyphosphates defined above can be utilized individually or as mixtures of two or more of

these materials. This includes so-called tetraphosphate, $M_4P_4O_{13}$ in which the ratio of M_2O to P_2O_5 is 3 to 2, and which is regarded here as a mixture of equal moles of the glassy phosphate $(MPO_3)_6$ and the crystalline phosphate $M_4P_2O_7$ and appears to give results substantially identical to a composition prepared with equimolar amounts of the two salts, M having the values indicated above. The amount of polyphosphate preferably employed is about 20% to 80% by weight of the anhydrous composition, although it is understood that in certain instances larger or smaller amounts of this material can be utilized.

The detergent ingredient of my composition should be a non-ionic or an anionic detergent, the non-ionic type being preferred. The non-ionic and anionic detergents useful in the invention are deemed to be those which are chemically stable in acid solutions having an acidity between pH 3 and 7. Mixtures of these two types of detergent can also be employed. Illustrative examples of non-ionic and anionic detergents useful for purposes of the invention are listed in Tables 1 and 2 below, but it is to be understood that these are only examples of many of these materials which can be used.

60 The detergent ingredient of my composition should be a non-ionic or an anionic detergent, the non-ionic type being preferred. The non-ionic and anionic detergents useful in the invention are deemed to be those which are chemically stable in acid solutions having an acidity between pH 3 and 7. Mixtures of these two types of detergent can also be employed. Illustrative examples of non-ionic and anionic detergents useful for purposes of the invention are listed in Tables 1 and 2 below, but it is to be understood that these are only examples of many of these materials which can be used.

3
TABLE 1
Non-Ionic Detergent

	Trade Name	
Polyethylene glycol alkyl phenylether.	Nomic 300	Sharples Chemicals, Inc.
Fatty acid alkanolamide.	Ninol 2012	Ninol Laboratory.
Polyoxyethylene thioether.	Sterox SK	Monsanto Chemical Co.
Polyethoxylate.	Teox 120	Blockson Chemical Co.
Alkylarylpolyether alcohol.	Triton X-100	Rohm & Haas Co.
Polyoxyethylene sorbitan.	Tween 21	Atlas Powder Co.

TABLE 2
Anionic Detergent

Sodium-ethylhexane sulfonate.	Tergitol EH	Carbide & Carbon Chemicals Corp.
Alkyl aryl sulfonate.	Nacconol	Allied Chemical & Dye Corp.
Na Salt of alkyl aryl poly-ether sulfate.	Triton 770	Rohm & Haas Co.

Nomic 300 has the following properties:

Appearance—clear, pale straw color
Cloud point—(1% aqueous solution)—56° C.
Specific gravity—20°/20° C.—1.06

Ninol 2012 is a diethanolamide condensation product of coconut fatty acid in which two mols of diethanolamine are condensed with one mol of fatty acid.

Sterox SK is ethoxylated alkyl thio ether having the following properties:

Specific gravity—25° C.—1.0345
Pour point—55° F.

Teox 120 has the following formula:

where R is a tall oil acid.

Triton X-100 has the following formula:

where x is from about 9 to about 10.

Tween 21 is sorbitan monolaurate which has been ethoxylated at the non esterified hydroxyls with ethoxy chains of variable lengths.

Tergitol EH is sodium 2-ethyl hexyl sulfate of the formula

C₂H₅

Nacconol is an alkyl benzene sulfonate of the formula:

where R is an alkyl group having from about 12 to about 18 carbon atoms.

The amount of detergent component in my composition is preferably between 1% and 25% by weight of the anhydrous composition, although larger or smaller quantities on occasion may be employed.

The third essential ingredient of my composition is a mono hydroxy aliphatic monocarboxylic acid such as hydroxy acetic acid, lactic acid, or mixtures thereof, hydroxy acetic acid being preferred. The amount of the hydroxy acid component employed is preferably from 5% to 50% by weight of the anhydrous composition, although again, as in the case of the polyphosphate and detergent components of my composition, the amount of the hydroxy aliphatic acid employed may be increased or de-

creased above and below the aforementioned range in some cases.

In formulating the compositions of my invention, I may mix together the ingredients, for example, alkali metal polyphosphate, non-ionic detergent, and hydroxy acetic acid, to form a single composition which can be packaged and when ready for use, added to water. If desired, however, the ingredients may be separately dissolved in water to give the solutions described below.

It is believed that a synergistic action takes place between the three above noted components of my composition when employed in aqueous solution, which gives results superior to and unexpected from, compositions containing only one or two of the ingredients of my composition, as regards effectiveness for removal of radioactive contamination, especially contaminants emitting alpha rays such as uranium and plutonium. However, I desire it to be understood that the invention is not to be limited by any theory as to the manner in which the components of my composition function.

The invention composition when dissolved in water forms a solution having a pH range of between about 3 and about 8, the preferred compositions with the range of ingredients noted above having a pH of between about 3.5 and about 5.5. It will be noted then that the pH of my solutions is generally slightly on the acid side in contrast to the alkaline solutions conventionally employed for this purpose.

The concentration of the anhydrous composition in the solutions can vary, a range of about 1 to about 8 ounces or more per gallon of solution being satisfactory, with a proportion of about 2 to 5 ounces per gallon preferred.

If desired, small amounts of other materials which do not affect the functioning of the main ingredients of my composition for removal of radioactive contamination, can be added to the compositions or solutions of the invention, e.g., small amounts of cationic detergents and small amounts of materials usually associated as impurities with the essential components of my composition, such as sulphates and chlorides. However, these additional materials are not essential to the invention.

In normal commercial laundering operations, the fiber of the materials being laundered is cleaned by strong alkalies followed by a subsequent acid sour, the purpose of the sour being to remove all alkalinity so that the clothing in contact with the skin will not cause irritation of the skin. The composition and process of my invention, in addition to their effectiveness for removal of radioactive contamination, have the added advantage for laundering purposes of not requiring a subsequent acid sour, since my composition in water solution produces a pH generally slightly on the acid side or sufficiently close to neutral, as indicated above, to avoid this additional step. At the pH of my solutions, which is in the vicinity of the pH of said acid sours, the cleaning solution will produce no irritating effect on the skin even if the fiber is inadequately rinsed. This advantage materially reduces the time of the operation and eliminates the need for the acid sour, resulting in additional economy of operation.

The tests on removability of radioactive contamination according to my invention were conducted on three types of radioactive sources, namely: uranium, plutonium, and soft beta radiation emitters. The plutonium was tested for removability of alpha radiation, the uranium for removal of alpha and the combination of beta and gamma rays, and the soft beta for removal of materials emitting the combination of beta-gamma rays. The materials emitting beta and gamma rays were included as one category because the counting devices determined the radiation level of both these products. The results of these tests showed removal up to 99% of contaminants emitting alpha rays and up to 100% of contaminants emitting beta-gamma radiation.

The tests were conducted in a washer or container constructed of stainless steel. In no instance was a redeposi-

tion of the radioactive emitters noted, indicating effectiveness of the invention composition and process for the removal of contamination from metal as well as clothing. The invention composition may also be effective in the removal of radicactivity from other types of surfaces such as concrete, rubber, canvas and wood. Temperatures of the laundering operation are those conventionally employed, e.g., from 120° F. to 180° F.

The following examples serve to illustrate the invention:

EXAMPLE 1

A composition according to the invention was added to water in a concentration of 2.6 ounces of the anhydrous composition per gallon of water. The pH of the solution was about 4. The composition consisted of the following ingredients:

Composition Y:	Percent by weight
Sodium hexametaphosphate	70.2
Alkylarylpolyether alcohol (Triton X-100)	2.3
Alkyl aryl sulfonate (Nacconol)	5.3
Hydroxy acetic acid	22.3
	100.0

The solution was tested on patches of cotton cloth contaminated with radioactive substances.

The test patches were contaminated with three known contaminants, namely, radioactive products of uranium and of plutonium, and material emitting soft beta rays. The uranium products emit alpha and beta-gamma rays, plutonium emits alpha rays and the soft beta emits beta-gamma radiation. The composition of the materials emitting soft beta rays was unknown. The cotton patches were subjected to a 15 minute wash in the solution at about 180° F. containing Composition Y and were then rinsed. Thereafter, the patches were dried in hot air dryers at about 180° F. The water used was tap water of 4.4 grains hardness.

Following treatment of the patches as described above, the contaminants remaining thereon were tested at three levels, arbitrarily chosen by the degree of emission. The low level contamination for beta and gamma emitters started at 400 counts per minute; the highest level of contamination for beta and gamma emitters was 40,000 counts per minute with the intermediate level approximately half way between. The alpha contamination derived from plutonium and uranium also started at 400 counts per minute with the high level contamination at 4,000 counts per minute and the intermediate approximately 2,000 counts per minute.

The results of a number of tests employing the above composition and procedure are as follows:

Contaminant	Percent Removed	
	Alpha	Beta-Gamma
Plutonium	95	
Uranium	79	29
Soft Beta		93

EXAMPLE 2

A second composition according to the invention was added to water in a concentration of 3.4 ounces of the anhydrous composition per gallon. The pH of the solution was about 4. The composition consisted of the following ingredients:

Composition Z:	Percent by weight
Sodium hexametaphosphate	58.3
Alkylarylpolyether alcohol (Triton X-100)	20.0
Alkyl aryl sulfonate (Nacconol)	4.2
Hydroxy acetic acid	17.5
	100.0

Tests similar to the tests of Example 1 were carried out using the same procedure, but employing Composition Z instead of Composition Y.

The results obtained were as follows:

Contaminant	Percent Removed	
	Alpha	Beta-Gamma
Plutonium	96	
Uranium	92	88
Soft Beta		91

Thus, it is seen that by increasing the concentration of nonionic detergent, i.e., alkylarylpolyether alcohol, in Composition Z over that in Composition Y, improved results are obtainable on removal of alpha uranium, and especially beta-gamma uranium.

EXAMPLE 3

The solution formed employing substantially Composition Z as in Example 2 was placed in a General Electric household washing machine equipped with automatic agitation. The test patches were subjected to treatment in said solution at 180° F. for a period of 12 minutes. The patches were then rinsed and dried, and were tested as described above for radioactive contamination. The results obtained were as follows:

Contaminant	Percent Removed	
	Alpha	Beta-Gamma
Plutonium	99	
Uranium	98	100
Soft Beta		90

It is seen that excellent removal of plutonium alpha and of both uranium alpha and beta-gamma took place, with fairly satisfactory removal of soft beta emitters.

EXAMPLE 4

Results similar to those of Examples 2 and 3 are obtainable by omitting the anionic alkyl aryl sulfonate detergent from Composition Z and replacing it with a like amount of the alkylarylpolyether alcohol non-ionic detergent or with a like amount of the hydroxy acetic acid.

EXAMPLE 5

Results similar to those of Examples 2 and 3 can be obtained by replacing the sodium hexametaphosphate of Composition Z with a like amount of sodium polyphosphate having a Na₂O:P₂O₅ ratio of 1.2.

EXAMPLE 6

Similar results to those of Examples 2 and 3 may be obtained by replacing the hydroxy acetic acid of Composition Z with a like amount of lactic acid.

EXAMPLE 7

Results comparable to, but not quite as effective as, those of Examples 2 and 3 are obtainable by replacing the sodium hexametaphosphate of Composition Z with a like amount of sodium tripolyphosphate or sodium pyrophosphate.

Comparative tests for removal of radioactive contaminants were run employing solutions according to the invention and prior art solutions, e.g., those containing a polyphosphate, sodium carbonate, trisodium phosphate and soap. In general, the invention composition containing a polyphosphate as above described, a non-ionic or anionic detergent, and hydroxy acetic or lactic acid, was superior in effectiveness to conventional laundering compositions and processes known for this purpose.

The laundering operation according to the process of the invention, preferably employing my polyphosphate, non-ionic detergent and hydroxy acetic acid composition, moreover has the advantage of being in the nature of a

normal cleaning or laundering procedure with the important and economical exception that it is not necessary to use the conventional acid sour and numerous rinses after cleaning. The invention composition is preferably slightly acid or almost neutral when dissolved in water and will therefore not produce chapping or skin irritation from retained alkalinity on the surfaces of the clothing, which is so noticeable with the highly alkaline compounds formerly used in laundry operations for radioactive decontamination purposes. Further, the solutions of the invention do not produce undesirable corrosion of the metal surfaces of the laundering equipment, e.g. made of Monel or stainless steel, with which such solutions come into contact.

While I have described a particular embodiment of my invention for the purpose of illustration, it should be understood that various modifications and adaptations thereof may be made within the spirit of the invention as set forth in the appended claims.

I claim:

1. A process effective for removal of radioactive contaminants from a surface, which comprises treating said surface with a solution in water of a composition which consists essentially of a water soluble polyphosphate of the group consisting of alkali metal and ammonium polyphosphates, a detergent of the group consisting of non-ionic and anionic synthetic detergents stable in acid solutions of a pH of 3 to 7, and a monohydroxy aliphatic monocarboxylic acid of the group consisting of hydroxy acetic acid and lactic acid, the range of ingredients in said composition being 20% to 80% polyphosphate, 1% to 25% detergent, and 5% to 50% hydroxy acid.

2. A process effective for removal of radioactive contaminants from a surface, which comprises treating said surface with a solution in water of a composition which consists essentially of a polyphosphate having a $M_2O:P_2O_5$ ratio of about 0.9 to about 1.3, M being a member of the group consisting of alkali metal and ammonium, a non-soap detergent of the group consisting of non-ionic and anionic synthetic detergents stable in acid solutions of a pH of 3 to 7, and a monohydroxy aliphatic monocarboxylic acid of the group consisting of hydroxy acetic acid and lactic acid, the range of ingredients in said composition being 20% to 80% polyphosphate, 1% to 25% detergent, and 5% to 50% hydroxy acid.

3. A process effective for removal of radioactive contaminants emitting alpha radiation from a surface, which comprises treating said surface with a solution in water

consisting essentially of an alkali metal polyphosphate having a $M_2O:P_2O_5$ ratio of about 0.9 to about 1.3, M being an alkali metal, a non-ionic detergent and hydroxy acetic acid, the range of ingredients employed by weight of the mixture of ingredients being as follows: 20% to 80% polyphosphate, 1% to 25% detergent and 5% to 50% hydroxy acid.

4. A process as defined in claim 3, wherein said alkali metal is sodium.

5. A process as defined in claim 4, said solution including an anionic nonsoap synthetic detergent stable in acid solutions of a pH of 3 to 7, said 1% to 25% of detergent including both said non-ionic and said anionic detergents.

6. A process effective for removal of radioactive contaminants including uranium and plutonium from clothing, which comprises treating said clothing with a solution in water consisting essentially of a water soluble polyphosphate which when dissolved in water in a concentration of about 31 grams per liter gives a solution having a pH of about 6 to about 8, a non-ionic detergent and hydroxy acetic acid, the range of ingredients employed based on the total weight of said ingredients being as follows: 20% to 80% polyphosphate, 1% to 25% detergent, and 5% to 50% hydroxy acetic acid.

7. A process as defined in claim 6, wherein said polyphosphate is sodium hexametaphosphate.
